UNITED STATES PATENT OFFICE.

ERIN M. KIRK, OF SEATTLE, WASHINGTON.

GREASE CARTRIDGE.

Application filed June 11, 1925. Serial No. 36,503.

This invention relates to an improvement in grease guns and more particularly to a means whereby the material may be introduced into the gun in a simple expeditious manner with an exactly proper load and without entailing the usual and objectionable direct handling of the material.

The invention consists in packing the grease in what may be termed original containers of readily frangible material, such as thin wax paper, or a readily disruptible membrane, with these containers or cartridges of a size to be readily inserted and more or less accurately fit diametrically the interior of the gun barrel. With these original containers of the material, ordinarily hard or semi-hard grease, the gun may be readily loaded in practically a single operation without the liability of soiling the hands or clothing, it being apparent that the cartridge when applied is readily disruptible under the pressure of the gun to permit the ejection of the grease in substantially the usual manner.

The invention is illustrated in the accompanying drawings, in which:

Fig. 1 is a view in elevation, partly in section, of the improved grease gun, a cartridge being shown in place therein.

Fig. 2 is an elevation of the cartridge.

The grease gun is of any ordinary or usual type, comprising a barrel 1, provided at one end with a removable cap 2, interiorly threaded to cooperate with the exteriorly threaded end of the gun barrel, and formed with a discharge projection 3, which if desired, may be formed for the connection of an extension to permit delivery of the grease in the usual manner. The opposite end of the gun is exteriorly threaded to receive a cap 4, in which is threaded a plunger stem 5 provided beyond the cap with an operating handle 6 and at that end to be extended within the barrel with a plunger 7.

The grease preferably of a hard or semi-

hard character is, for the purpose of the present invention, packed within a frangible or disruptible container 8 forming a closed cartridge which is of a size of course to more or less snugly fit within the barrel 1, particularly as to the relative diameters of the barrel and cartridge.

In charging the gun, the cartridge is introduced into the barrel after the removal of the cap 2, and after the re-application of the cap, the gun is operated in the usual manner. It is preferred that the plunger 7 is of a diameter to permit the wall of the cartridge to be interposed between the peripheral edge of the plunger and the wall of the gun barrel, so that the plunger may move longitudinally of the barrel in operation of the gun and leave the wall of the cartridge against the wall of the gun barrel. Under any circumstances, it will be apparent that the operation of the plunger will serve to break the material of the cartridge and force the grease from the gun in the usual manner.

After the contents of the cartridge has been used, the covering thereof may be readily removed from the gun and a fresh cartridge inserted when necessary.

Claim:

A grease cartridge for use in grease guns, comprising an integral cartridge constructed throughout of frangible material adapted to fit snugly within the grease gun and to contain grease, the cartridge including frangible ends to completely close the cartridge against the loss of contained grease when the cartridge is being handled outside the grease gun, the interior diameter of the cartridge corresponding to the exterior diameter of the piston of the grease gun to avoid interference with said wall in the use of the cartridge.

In testimony whereof I affix my signature.

ERIN M. KIRK.
